Synnestvedt & Lechner

UNITED STATES PATENT OFFICE.

JOHN L. MOHUN, OF OMAHA, NEBRASKA, ASSIGNOR TO FRANKLIN RAILWAY SUPPLY COMPANY, A CORPORATION OF DELAWARE.

LOCOMOTIVE FIRING EQUIPMENT.

Application filed June 21, 1921. Serial No. 479,219.

My invention relates to locomotive firing equipment, and is especially concerned with apparatus for automatically stoking steam locomotives and shaking their grates. I aim 5 to correlate these closely related firing operations in such a way that they can both be carried out effectively and efficiently by simple and unitary apparatus. I also aim to provide for (or permit) such relatively 10 independent, flexible regulation of these operations that each can be performed according to the requirements of the locomotive under the most widely varied operating conditions,—yet still in due correlation 15 with the other. A further advantage of my invention is its ready adaptability to types of stoking and grate-shaking apparatus which are now very widely used, with but little alteration of the more important parts 20 of such apparatus, so that the invention can be applied to a great many locomotives now in service quite easily and expeditiously, with little loss of time from service and at relatively small cost.

25 How these and other advantages can be obtained in connection with my invention will appear from my description hereinafter of a preferred form and embodiment of the invention.

30 In the drawings, Fig. 1 is a fragmentary and somewhat diagrammatic side view illustrating the practical application of my invention in connection with the well-known “duplex” type of automatic stoker and with 35 shaker mechanism in part of the well-known “Franklin power grate shaker” type. In this figure, the firing equipment or apparatus appears in side elevation, and the fire box of a locomotive to which it is applied 40 appears in vertical longitudinal section.

45 Fig. 2 is a somewhat diagrammatic rear view, in elevation, of the locomotive and its firing equipment, some parts being broken away or in vertical mid-section as indicated by the line 2—2 in Fig. 3, and the parts at the upper end of one of the inclined elevator casings being also broken away.

50 Fig. 3 is a fragmentary plan view of certain operating parts, some of which are

broken away or in horizontal mid-section as indicated by the line 3—3 in Fig. 2.

Fig. 4 is a fragmentary detail view, in elevation, and on a larger scale, illustrating part of the grate-shaking mechanism shown 55 in Fig. 2, certain parts being in section.

Fig. 5 is a detail view illustrating certain parts of the grate-shaking mechanism and their order of arrangement along a shaft on which most of them are mounted. 60 As shown, these various parts are individually turned 90° from their working positions, into parallelism with the plane of the paper.

Fig. 6 is a somewhat fragmentary plan 65 view illustrating features of the usual coal-feeding mechanism of the “duplex” stoker and their relation to various special parts illustrated in the other figures,—certain structural parts being removed and others 70 broken away or in section to expose various mechanical parts to view.

As already stated, the stoker mechanism here shown is of the well known “duplex” type, so that no more than a general description 75 thereof is required. Only the more important parts located on the locomotive are shown, the tender and the parts thereon being omitted for the sake of clearness.

In this “duplex” stoker, the coal-feeding 80 mechanism comprises a rotary conveyor screw 10 extending from the tender to the locomotive through a trough or conduit (not shown), and delivering the coal (in a suitably ground or powdered state) into a receptacle or hopper 11 beneath the deck or cab floor 12. The coal-feed mechanism also comprises elevators in the form of rotary conveyor screws 13 extending from said hopper 11 up through the cab floor, in 85 divergently inclined casings 14, and delivering to distributor tubes 15 that project into the locomotive fire box 16 through openings 17 in its rear wall,—one at either side of, and rather above, the usual furnace door 18. 95 The coal is continually blown into the fire box through the tubes 15 by steam, and is thus distributed over the grate 20 in a suitably uniform manner,—the supply of steam to the tubes 15 being regulable to give 100

a proper distribution of the amount of coal required under different operating conditions of the locomotive.

The fuel feed mechanism comprising the conveyor 10 and the elevators 13 is operated or driven by power from an automatic actuator 22 in the form of a double-acting reciprocating automatic steam engine, mounted beneath the deck 12 and, as shown, below 10 and to the rear of the fire box 16 of the locomotive boiler, to one side of the hopper 11. The piston rod 23 of the actuator engine 22 extends and reciprocates or vibrates transversely of the locomotive, and to it is attached 15 a reciprocating slide bar 24 with toothed racks 25 and 26 on its rear and upper sides, respectively. This rack bar 24, therefore, also extends transversely of the locomotive, at the rear of the boiler, beneath 20 the cab floor 12.

With the rack 25 mesh helical gears 27 fixed on the lower ends of the inclined shafts 28 of the elevator screws 13, so that these shafts receive a vibratory rotation as 25 the rack bar 24 reciprocates,—i. e., the shafts oscillate, or revolve first in one direction and then in the other. The elevator screws 13 are actuated by the shafts 28 through single-acting pawl mechanisms 29, 30 so that the motion of the screws is an intermittent, or periodic, unidirectional step by step rotation such as to raise the coal. Thus the coal is delivered to the distributors 15 in 35 definite periodic charges corresponding in amount to the rotary "step" of the screws, and in frequency to the rate of reciprocation of the actuator 22. The pawl mechanisms that actuate the screws 13 can be adjusted individually to vary the rotary step of the 40 screws (or even thrown out of action altogether, so as to stop the feeding of fuel to one or both distributor tubes 15) by means indicated at 30; and the rate of reciprocation of the actuator 22 can be varied (or 45 the actuator stopped) by valve means comprehensively indicated at 33.

With the rack 26 meshes a gear 34 fixed on a rotary drive shaft 35 which extends fore and aft of the locomotive, and ultimately 50 connects with the tender conveyor or screw 10 through a single-acting pawl mechanism 36. The oscillatory shaft 35 thus drives the screw 10 with an intermittent, or periodic, unidirectional step by step rotation. The 55 pawl mechanism in question can be adjusted to vary the rotary step of the conveyor 10 and the amount of the periodic charges delivered to the hopper 11 in proper correspondence with the operation of the elevators 13,—or even thrown out of action altogether, so as to stop the feeding of fuel to the 60 hopper. The frequency of delivery to the hopper 11 is varied (or delivery stopped entirely) by the control 33 of the reciprocation 65 of the actuator 22 described above.

It will be seen, therefore, that the actuator 22 is the source of power for the entire fuel feed mechanism, and that this actuator has vibratory actuating or drive connection with that mechanism: through the oscillatory rotary members 27, 28 to the elevators 13; through the oscillatory rotary members 34, 35 to the tender conveyor; and through the reciprocating rack bar member 24 to both elevators and to the tender conveyor too, 70 the racks 25 and 26 of the member 24 meshing with the respective gears 27, 27 and 34 that drive the elevators 13 and the tender conveyor, as already described.

Passing, now, from the fuel-feeding mechanism to the grate-shaking mechanism, it will be seen that the grate 20 in the fire box 16 comprises a number of transverse grate-bars 40 which may be mounted to rock back and forth in the usual manner. These bars 40 80 are interconnected in groups or sections 41, 42, etc., as usual, (only two such sections appearing) by links 45 pivoted at 46 to depending lugs 47 on the bars. Rods 48 pivoted to the links 45 at 49 connect the sections 41, 90 42, etc., to the lower arms of corresponding two-arm oscillatory grate-levers 50, 51, etc., which are arranged in pairs at either side of the fire box 16 and are free to turn about an oscillatory shaker shaft 55 extending 95 transversely of the locomotive at the rear of the fire box.

As shown in Fig. 4, the shaker shaft 55 is mounted in short square-holed journal-sleeves 56 whose bearings are in brackets 57 secured to the rear wall of the boiler, and the levers 50, 51 are journalled on these same sleeves 56. Between each pair of grate-levers 50, 51, etc., and their sleeves 56 are upward-extending oscillatory arms 60, 61 mounted on the shaft 55 in direct anti-turning engagement with it. To the arm 60 (and likewise to the arm 61) are hinged latch yoke plates 62 adapted to be swung down to engage the upper arms of the levers 50, 51, or swung up out of engagement. (As shown, the righthand latch 62 is engaged with the lever 50, and the lefthand latch is swung up into inactive position.) The latches 62 are securely held in either of these positions by engagement of spring-pressed plungers 63 (mounted in a cross-piece 64 on the arm 60) with the squared sides of their pintle-lugs 65.

By proper manipulation of the latches 62, it will be seen, the grate sections 41, 42, etc., can be selectively connected with the oscillatory shaft 55 and shaken singly, in fore and aft or right and left pairs, or all together, 125 etc., as desired. At the same time, the bars 40 of the grate sections not being shaken can be locked in their normal horizontal or "up-right" positions by means of locking-yokes 66 (similar to the latches 62) pivoted to the 130

brackets 57 beside each of the grate-levers 50, 51, etc.

For the purpose of operatively connecting the grate-shaking mechanism just described with the actuator 22, a bevel gear 70 is fixed 5 on the forward end of the fore and aft shaft 35 by which the conveyor 10 is driven. This oscillatory gear 70 meshes with a somewhat larger bevel gear 71, which is loose on 10 the end of a short transverse stub-shaft 72 fixed in a part of the casing 73 that encloses the rack bar 24 and various associated operating parts. (In practice, of course, the gears 70 and 71 are also enclosed.) At the 15 back of the gear 71 is a coaxial shaker drive member in the form of a crank-disk 75, adapted to turn with the gear about an axis transverse of the locomotive. With the ordinary "duplex" stoker mechanism and the 20 relative sizes of the gears 70 and 71 shown, the disc 75 will oscillate or vibrate back and forth about $\frac{1}{3}$ of a revolution. The crank-pin 76 of the disc 75 is connected by a link rod 77 to the depending arm 78 of a rocker 25 member 80 at the rear of the boiler, fulcrumed at 79. On the shaker-shaft 55, directly in front of the rocker 80, is fixed a rocker member 81, similar to the rocker 80, but without any depending arm. As the 30 rocker 80 oscillates or vibrates back and forth, its ends strike and actuate the ends of the rocker 81, and thus oscillate or vibrate the shaker shaft 55 and rock the grate bars 40.

35 The amplitude of movement of the rocker 81 and the shaking of the grate bars 40 can be regulated by varying the relative positions of the fulcra 55 and 79 of the rockers 81 and 80. For this purpose, the fulcrum 79 is mounted and supported on the lower arm on a bell-crank lever 82, which is 45 itself fulcrumed and supported on a bracket 83 attached to the rear end of the boiler fire box 16, above the cab floor 12. The other arm of the lever 82 is forked and engaged between arcuate shoulders on a nut-block 84 threaded on an upright screw shaft 85, mounted in bearings in a housing 86 in the cab and provided with an operating 50 handwheel 87. By shifting the fulcrum 79 toward or from the fulcrum 55, it will be seen, the rocking of the grate 20 can be regulated and made as violent or as gentle as desired, or even stopped altogether,—since 55 the rocker 80 can be varied from continual contact with the rocker 81 as the one extreme to never striking it at all as the other.

Like that afforded by the latches 62, the regulation of the grate shaking action by 60 means of the rockers 80 and 81 is independent of the fuel feed mechanism,—except, of course, as affected by the general regulation of the actuator 22 by its control and regulating means 33.

65 For the purpose of preventing injury or

breakage in case the grate 20 (or its connections to the disc 75) should become jammed or blocked from any cause, the connection between disc 75 and gear 71 is preferably a yielding or break-down one. As shown, 70 there are radially extending transverse triangular ridges 90 on the back of the gear 71 and corresponding radially extending triangular grooves 91 in the disc 75. The disk 75 is pressed against the gear 71 by a helical 75 compression spring 92 acting between the bottom of a recess in the disc (that accommodates the spring) and the head of a pin 93 (screwed into the end of the shaft 72) on which the disc is mounted. Normally, the 80 ridges 90 remain seated and engaged in the grooves 91 and constrain the disc 75 to oscillate with the gear 71; but if the resistance of the gear becomes excessive, the ridges ride out of the grooves at every oscillation of the 85 gear,—until the rocker 80 is shifted out of actuating distance from the rocker 81, the actuator 22 or the shaft 35 stopped, or the obstruction removed.

I claim:

1. Automatic locomotive firing equipment comprising the combination of fuel feed mechanism, grate-shaking mechanism, a common automatic actuator for said fuel feed and grate-shaking mechanisms, and a 95 breakdown operating connection from said actuator to said grate-shaking mechanism, with means for regulating the action of said grate-shaking mechanism independently of 100 said fuel feed mechanism.

2. Automatic locomotive firing equipment comprising, in combination, fuel feed mechanism; grate-shaking mechanism; a common automatic actuator for said fuel feed and grate-shaking mechanisms; and means for 105 regulating the action of said grate-shaking mechanism independently of said fuel feed mechanism comprising oscillatory actuating and actuated rocker members and means operable from the locomotive cab for varying the relative positions of the fulcra of 110 said rocker members.

3. Automatic locomotive firing equipment comprising the combination of fuel feed mechanism, shaking grate mechanism, and a 115 common automatic actuator for said fuel feed and shaking grate mechanisms, with means for operating the shaking grate mechanism from said actuator comprising a shaker drive member with axis transverse of the locomotive, an oscillatory rocker member operatively connected with said shaker drive member, another oscillatory rocker member operatively connected to the grate and fulcrumed at the rear of the boiler for 120 actuation by the first-mentioned rocker member, and means for varying the relative positions of said rocker members to regulate 125 the shaking of the grate.

4. Automatic locomotive firing equipment 130

comprising the combination of fuel feed mechanism, shaking grate mechanism, and a common automatic actuator for said fuel feed and shaking grate mechanisms, with 5 means for operating the shaking grate mechanism from said actuator comprising a shaker drive member with axis transverse of the locomotive, an oscillatory rocker member having an operative connection to 10 said shaker drive member, another oscillatory rocker member operatively connected to the grate and fulcrumed at the rear of the boiler in front of the first-mentioned rocker member, for actuation thereby, and means 15 for shifting the fulcrum of said first-mentioned rocker member toward or from the other to regulate the shaking of the grate.

5. Automatic locomotive firing equipment comprising, in combination, fuel feed mechanism; an automatic actuator with connection to said fuel feed mechanism reciprocating transversely of the locomotive; grate-shaking mechanism; and means for actuating said grate-shaking mechanism from the 20 aforesaid transverse connection, including an oscillatory break-down connection.

6. Automatic locomotive firing equipment comprising, in combination, fuel feed mechanism including a drive shaft extending fore 30 and aft of the locomotive; a member with axis transverse of the locomotive geared to said drive shaft; and means for transmitting motion from said member to the locomotive grate to shake the latter, comprising oscillatory actuating and actuated rocker members and means for varying the relative 35 positions of the axes of said rocker members to regulate the shaking of the grate.

7. Automatic locomotive firing equipment comprising, in combination, fuel feed mechanism; an automatic actuator with connection to said fuel feed mechanism extending transversely of the locomotive at the rear of the boiler beneath the cab floor; a shaker 40 drive member with axis transverse of the locomotive operated by the aforesaid transverse connection; and means for transmitting motion from said shaker drive member to the locomotive grate to shake the latter comprising oscillatory actuating and actuated rocker members and means operable 45 from the cab for varying the relative positions of the fulcra of said rocker members to regulate the shaking of the grate.

55 8. Automatic locomotive firing equipment comprising, in combination, fuel feed mechanism; grate shaking mechanism; and a common automatic actuator for said fuel feed and grate-shaking mechanisms, with a 60 connection to one of them reciprocating transversely of the locomotive.

65 9. Automatic locomotive firing equipment comprising, in combination, fuel feed mechanism and an actuator therefor with a connection thereto reciprocating transversely of

the locomotive; and means for transmitting vibratory motion from said connection to the locomotive grate to shake the latter.

10. Automatic locomotive firing equipment comprising, in combination, fuel feed 70 mechanism including an oscillatory drive shaft extending fore and aft of the locomotive; a member with axis transverse of the locomotive geared to said drive shaft, and means for transmitting motion from said member to the locomotive grate to shake 75 the latter.

11. Automatic locomotive firing equipment comprising, in combination, fuel feed mechanism; an automatic actuator with 80 connection to said fuel feed mechanism reciprocating transversely of the locomotive at the rear of the boiler beneath the cab floor; a shaker drive member with axis 85 transverse of the locomotive operated by the aforesaid transverse connection; and means for transmitting motion from said shaker drive member to the locomotive grate to shake the latter.

12. Automatic locomotive firing equipment comprising, in combination, fuel feed 90 mechanism; an automatic actuator with connection to said fuel feed mechanism extending transversely of the locomotive at the rear of the boiler beneath the cab floor; a shaking grate mechanism, and a shaker 95 drive member with axis transverse of the locomotive operated by the aforesaid transverse connection; and means for transmitting motion from said shaker drive member to the locomotive grate to shake the latter comprising an oscillatory rocker member at the rear of the boiler with its fulcrum mounted thereon operatively connected to the grate, and an oscillatory 100 rocker member for actuating the rocker aforesaid supported from the boiler and operatively connected with the aforesaid shaker drive member.

13. Automatic locomotive firing equipment comprising, in combination, fuel feed 110 mechanism including an elevator; an automatic actuator with connection to said elevator through a reciprocating rack bar; and means for transmitting vibratory motion 115 from said connection to the locomotive grate to shake the latter.

14. Automatic locomotive firing equipment comprising, in combination, fuel feed mechanism including a tender conveyor; an oscillatory drive connection for said conveyor; and means for transmitting vibratory motion from said drive connection to the locomotive grate to shake the latter. 120

15. In combination, a firebox, a plurality 125 of grate sections within said firebox, stoker mechanism including a motor for supplying fuel to said firebox, and mechanism including a movable member for operating said sections from said motor, and also including 130

means for selectively disconnecting said sections from said movable member.

16. In combination, a firebox, a grate comprising independently movable sections, 5 a grate moving member, means for selectively detachably connecting said sections to said member whereby said sections may be operated either independently or simultaneously, and means for operating said 10 member.

17. In combination, a firebox, a sectional grate therefor, stoker operating mechanism, a member reciprocated by said mechanism, and means for selectively detachably connecting said grate sections to said member for operating said sections.

In testimony whereof I have hereunto signed my name.

JOHN L. MOHUN.
